UNITED STATES PATENT OFFICE.

ERNEST O. FREDERICS, OF NEW YORK, N. Y.

HAIR-DRYING MACHINE.

Application filed October 14, 1921. Serial No. 507,654.

To all whom it may concern:

Be it known that I, ERNEST O. FREDERICS, residing at New York, in the county and State of New York, have invented certain new and useful Improvements in Hair-Drying Machines, of which the following is a specification.

This invention relates to improvements in drying apparatus, and more particularly to apparatus commonly employed for drying hair and like substances.

One of the objects of the invention is to provide new and improved apparatus of this character, which will operate in a highly efficient manner to perform functions for which it is constructed.

Another object of the invention is to provide a portable hair drying apparatus which is of exceedingly compact structure, and in which the centre of gravity is such that the apparatus may be freely moved from place to place without danger of the same tipping over.

Another object of the invention is to provide in an apparatus of the above character, new and improved means for heating the current of air forced through said device by the motor driven fan.

A further object of the invention is to provide new and improved means for regulating the amount of heat imparted to the current of air passing through the apparatus.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, wherein I have shown a preferred form of embodiment of my invention:

Figure 1 is an elevational view, partly in vertical section, showing a portion of the interior construction of my improved device.

Figure 2 is a view similar to Figure 1, but taken at right angles to said last mentioned figure.

Figure 3 is an elevational view of the heating element.

Figure 4 is a transverse sectional view taken through the heating element on the

line 4—4 of Figure 3, looking in the direction of the arrows, showing one means for supporting the same within the machine.

Figure 5 is an elevational view showing a different form of means for supporting the heating element.

Figure 6 is a cross-sectional view through a heating element, slightly different construction from that shown in Figures 3 and 4.

Figure 7 is a perspective view showing means for supporting the heating element, illustrated in Figure 5.

Figure 8 is a transverse sectional view taken on line 8—8 of Figure 2, looking in the direction of the arrows; and

Figure 9 is a diagrammatic view, showing the wiring connections controlling the motor, and the heating element.

Referring now to the drawings, wherein similar reference characters refer to similar parts throughout the several views of the drawings, the reference numeral 1 denotes the casing of my improved machine, the latter being formed of metal and clamped at its lower end by means of the screws 2, to a base portion 3. The casing is provided near its lower end with a circularly formed air inlet opening 4, which is disposed directly opposite the blades 5 of a fan 6, mounted upon the shaft 7 of the electric motor; the casing of which is shown at 8. The casing of this motor is clamped to the side wall of the casing 1.

An arm or bracket 9, extending upwardly from the base member 3, is connected to the motor casing 8, by the clamp bolts 10. Inasmuch as the motor casing 8 is fastened to the main casing 1, it will be seen that the said casing 1, including the motor casing, is supported at two spaced points upon the base member 3. The support for the entire machine comprises a base member 11 in the form of a tripod, the legs of which are furnished with the usual casters 12, the central portion of said tripod being provided with an aperture 13, adapted to receive the hollow shaft 14, of the base member 3; a shoulder 15 upon said base member 3 resting upon a shoulder 16 of the tripod, which shoulder surrounds the centrally disposed aperture 13.

The bearing thus provided for the base member 3 is such that the entire casing and enclosed parts are freely rotatably upon the tripod. In this connection it will be noted

that the motor being the heaviest part of the device is located directly above the tripod, so that the centre of gravity of the apparatus is relatively low or near the floor, thereby increasing the stability of the device upon its feet, making it difficult to tip it over.

The casing 1 is divided in two parts 17 and 18, which are joined respectively by 10 means of the collar 19, which collar is provided exteriorly with a circular wheel or handle 20, carried by the brackets or arms 21. By grasping this handle, which extends entirely about the casing, it will be 15 seen that the entire apparatus may be freely moved to any desired position.

Hinged as at 22 to the upper curved end 23 of the part 17 of the casing 1, is a flexible tube 24, having the exit opening or nozzle 25. This tube normally hangs by gravity, 20 in the position shown in Figure 2, but is adapted to be swung upwardly so that the inlet end 26 thereof will be carried into registry to the exit end 23 of the part 17 of 25 the casing; a spring catch 27 engaging with an internal shoulder 28 operating to hold the flexible tube in said last mentioned position. The tube 24 is preferably composed of any suitable material. In practice I have 30 found that an outer layer 29 of leather, and an inner layer 30 of canvas, may be used in this connection; a coil spring 31 operating to hold the tube in a distended condition, and also permitting the same to be bent or 35 flexed, as when it is desired to manipulate the nozzle 25 to various positions with respect to the head of the person whose hair is being subjected to the current of air discharged from the apparatus.

40 The heating element support 32 is mounted within the section 17 of the casing 1, and is generally of a rhomboidal or double frustoconical shape or form in elevation. In cross-section, as shown in Figures 4, 6 and 8, 45 it has the form of a cross, having radially extending arms 33, 34, 35 and 36, which arms it will be noted extend from one end to the other of the heating element support. The edges of each of the arms 33 to 36 50 inclusive, are preferably formed with small recesses or notches 37, which form seats for the resistance wire 38, which is supported by and coiled about the said heating element from one end to the other thereof. 55 This support is constructed of an insulating and high heat resisting material. Various substances may be used in this relation. In practice I have found that a block of lava is very efficient for use in this connection.

60 In the embodiment of my invention, shown in Figures 3, 4 and 6, this block or heating element support, which I have designated by the reference numeral 39, is clamped between the straps 40 and 41 by means of the clamp screws 42, set screws 43 received

in a circular groove 44 provided on the lower end 45 of the block, assisting the straps 40 and 41 to hold the heating element support against displacement.

Guides 46 clamped to the upper end of 70 the block 39, engage the inner surface of the section 17 of the casing and operate as steadyng or supporting means to prevent lateral displacement of the upper end of the heating element support. The strap 41 75 is clamped to the inner surface of the ring 19, as clearly shown in Figure 2 of the drawings, whereby the entire heating element support is rigidly supported within the section 17 of the casing. 80

In Figures 5 and 7, instead of clamping the lower end of the block 39 between the straps 40 and 41, a plate or base member 47 is provided, upon which the lower end of the block rests, and upon which it is fastened as by means of the clamp screws 48, 85 said plate having downwardly extending integrally formed ears 49, which are clamped to a bracket 50, the flanged ends 51 of which are fastened to the inner surface of the 90 ring 19, in a manner similar to which the strap 41 is fastened thereto.

By reason of the double tapered form of the lock 39 of the heating element support, it will be seen that substantially the entire 95 volume of air passing through the apparatus is carried into contact with the resistance wire, the space between the cross members or blades 33 to 36 inclusive of said block, forming passageways through which 100 the current is freely projected.

It will be understood, of course, that the block 39 also becomes highly heated by the resistance wire, so that the current of air 105 passing through the casing is brought into intimate contact with this highly heated body including both the block and the resistance wires, is in turn heated thereby, and is discharged from the apparatus through the nozzle 25 in this heated condition. 110

The lower end of the block 39 is provided with the terminals 52 and 53, which terminals are connected with the resistance wire, and which are in turn connected with the leading-in wires 54 and 55, the latter extending from the switch 56, carried upon a bracket 57 of the ring 19, said switch having the usual operating handle or button 58. 115

Located in the hollow shaft 14 of the base member 3 is a resistance element or rheostat 59. This resistance element or rheostat is connected through one of the leading-in wires of the feed cable 60, through the switch 56 with the motor, whereby the latter may be driven at variable speeds, thus causing a greater or less quantity of air to be discharged through the machine, whereby the temperature of the air may be varied, while maintaining a constant temperature 120 of the heating element. 125

Referring now to the electrical equipment of the machine as illustrated in the diagram of Figure 9, the reference numeral A designates a five pole switch—B the motor,—C the resistance or rheostat employed to vary the speed of the motor,—and D is the heating element.

The five binding posts of the switch are designated *a*, *b*; *c*, *d* and *e*. The terminal *a* is connected to one side of the main line, and the terminal *b* is connected to a point *c'* of the resistance coil or rheostat *c*. The wire connected to the point *c* after passing through the heater D is shunted to the other terminal of the main line. Terminal *f* of the motor B is shunted to the same line as at *f'*. The pole *d* of the switch is connected at the point *c''* of the resistance *c*. The switch terminal *e* is connected with the rheostat terminal *c''* as shown on Fig. 9. The other terminal *g* of the motor B is connected to the resistance C at *c''*. The switch has the following positions:

First position:—Connecting the pole *a* with *b*, current going through the entire length of resistance C, and then through the motor B, whereby the motor is run at low speed.

Second position:—The pole *a* is connected with the poles *c* and *d*, the current going through the heater D and also through two-thirds of the resistance C, and then through the motor. This runs the motor at the medium speed.

Third position:—The pole *a* is connected to the poles *c* and *e*—current passing through the heater D, and through the remaining portion of the resistance C, and then through the motor B. This runs the motor at the full speed.

In the fourth position, with current off, all the binding posts of the switch A are disconnected. It will be noted that in all the working positions of the switch, the motor and heating unit are connected in parallel.

It will be also observed that inasmuch as the heating unit has a fixed temperature, the variation of the speed of the motor driven fan causing a variable quantity of air to be discharged through the machine, the temperature of the air may be varied at will.

It will accordingly be seen that I have provided a machine well adapted to attain, among others, all the ends and objects above pointed out, in a simple and efficient manner. The centre of the gravity of the machine being low, makes the same very difficult to be tipped over when moved from

one place to another. The handle by which the machine is moved is located in a convenient position and may be readily grasped by the hand of the operator. The switch being carried by this manipulating handle is also in a most convenient position to be manipulated by the operator.

Moreover, the construction and form of the heating element is such that substantially all of the air passing through the machine comes in direct contact either with the heating wire itself, or with the heated support upon which the resistance wire is mounted.

Another advantage accruing by reason of the construction shown is that all the operating parts of the device, save the switch, are enclosed within the casing, thereby reducing to a minimum the chances of the machine becoming disordered or deranged through careless handling on the parts of operators.

As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. In a hair drying machine, the combination with a casing, of a fan, a unitary refractory heating element support having tapering end portions, cruciform cross-section and being supported in the casing in the path of air driven by the said fan, a resistance wire wound upon the said support, a switch for controlling current to said resistance, the said casing having a hinged flexible end portion whereby the casing may be extended in length beyond said support.

2. In a hair drying machine, the combination with a casing, of a fan, a unitary refractory heating element support having its ends connected with the interior of the casing and arranged in the path of the air from said fan, a resistance wire wound upon the said support, a switch for controlling the said resistance, a stand for carrying the casing, means whereby the said support and resistance wire and switch and the end portion of the casing may be turned upon the stand while the stand retains a stationary position.

In testimony whereof I affix my signature.

ERNEST O. FREDERICS.
